UNITED STATES PATENT OFFICE.

JOHN A. HEBB, OF UNIONTOWN, PENNSYLVANIA, ASSIGNOR TO THE HEBB COKE DRAWER CO., OF UNIONTOWN, PENNSYLVANIA.

CONVEYING MECHANISM FOR COKE-DRAWING MACHINES.

SPECIFICATION forming part of Letters Patent No. 728,168, dated May 12, 1903.

Application filed August 14, 1902. Serial No. 119,620. (No model.)

To all whom it may concern:

Be it known that I, JOHN A. HEBB, a citizen of the United States, residing at Uniontown, in the county of Fayette and State of Pennsylvania, have invented certain new and useful Improvements in Conveying Mechanism for Coke-Drawing Machines, of which the following is a specification, reference being had therein to the accompanying drawings, forming part of this specification, in which—

Figure 1 is a plan view of my improved coke drawing and conveying machine, showing it in position in front of an open door, portions of the traveling conveyer and the beam being broken away. Fig. 2 is a detail cross-sectional view on the line II II of Fig. 1. Fig. 3 is a view in side elevation of the apparatus. Fig. 4 is a longitudinal vertical section through the delivery-conveyer, indicated by the line IV IV of Fig. 1. Fig. 5 is a similar view indicated by the line V V of Fig. 1, showing the receiving-conveyer in elevation. Fig. 6 is a plan view showing the driving means for both conveyers.

My invention relates to apparatus for drawing coke from the oven and for conveying it away therefrom for delivery into cars for transportation or upon the yard.

The apparatus consists generally of a moving structure adapted to travel forward and back in front of the ovens, provided with a turn-table carrying a reciprocating beam adapted to be extended into and withdrawn from the oven to empty the contents therefrom.

The present application refers more particularly to the conveying mechanism which receives the coke from the oven-door and conveys it away therefrom at whatever position the machine may assume and finally delivers it as indicated.

Referring now to the drawings, A represents the framework of a portable carriage carrying a turn-table B, upon which are mounted the various manipulative portions of the machine.

Mounted in suitable bearings is a main shaft 4, driven at one end by a suitable prime

mover, as a steam-engine, electric, or other motor. Extending at right angles to shaft 4 and on substantially the same level is a counter-shaft 5, to which movement is imparted from shaft 4 by bevel-wheel 10 thereon gearing into bevel-wheel 9 on vertical shaft 6, which bevel-wheel in turn meshes into the bevel-wheel 11 on shaft 5, so that when main shaft 4 is driven shaft 5 will also be continuously driven in the direction indicated by the arrows. From these main shafts all of the various operations of the machine are transmitted, the conveyers being driven by sprocket-wheels mounted on the ends of shafts 4 and 5, respectively, as shall be hereinafter described.

27 is the reciprocating beam, adapted to be extended into and withdrawn from the oven and provided at its forward end with a rake-head 31, adapted to engage a portion of the coke in the oven and to draw it out through the door and to discharge it upon the receiving-conveyer, the beam being manipulated by suitable gearing fully described and shown in other contemporaneously filed applications bearing the serial numbers 119,617, 119,618, and 119,619.

At the side of the machine adjacent to the oven is located the conveyer C, consisting of a series of slats 81, forming an endless apron, secured upon and carried by sprocket-chains 84. The chains are carried upon sprocket-wheels 82 and 83, mounted on the head-shaft 85 and tail-shaft 86, respectively, carried in bearings on longitudinal members 87 or other suitable framework rigidly supported from framework A. The head-shaft 85 is driven through sprocket-wheel 88 on shaft 5 and chain 89, passing around driven sprocket-wheel 90, by which continuous movement is imparted to the conveyer during the rotation of the counter-shaft 5.

Arranged at right angles along one end of the apparatus is the conveyer D, which is of any suitable length adapted to the width of the yard or the distance to which it is desired to convey the coke, and this conveyer is generally similar to the one just described, the

slats, however, being somewhat separated to permit of the escape of the dust or small particles of coke. The slats 81' are mounted upon sprocket-chains 84', passing around sprocket-
5 wheels carried by head-shaft 91 and tail-shaft 92, the head-shaft being mounted in bearings rigidly supported from the framework of the machine.

The tail-shaft 92 is mounted in bearings in
10 the outer end of the supporting-framework 97, which may be rigidly carried upon suitable supporting mechanism extending outwardly from the machine, which is preferably pivoted to said supporting-framework
15 at 98 adjacent to the head-shaft, thereby permitting the inclination of the conveyer to be varied as desired. The pivotal bearing 98 is adjacent to the driving sprocket-wheel 94, so that variations in the height of the conveyer will not affect the tension of the driving sprocket-chain. The conveyer D is driven by sprocket-wheel 94 on shaft 4 and chain 95, passing around a driven sprocket-wheel 96, mounted on tail-shaft 92, the speed of the
20 conveyer, as is also the case with the conveyer C, being regulated by the relative proportions of the driving and driven sprocket-wheels.

For the purpose of preventing clogging of
30 the apparatus the speed of conveyer D is somewhat greater than that of conveyer C, so that the coke discharged on conveyer D will always be carried away somewhat faster than it is received.

35 Conveyer D is supported at its outer end or at any intervening position by any suitable framework, either extending outwardly from the main frame or downwardly to the ground from the conveyer in the manner of a
40 prop; but as various means may be utilized for this purpose, the supporting devices are not necessarily specifically shown or described.

As shown by the drawings, the general level of the first conveyer C is but slightly
45 below the level of the oven-floor, but is considerably higher than the inner end of the conveyer D, and the coke from conveyer C is discharged upon an inclined apron or floor 99, extending downwardly from its delivery
50 end to the inner end of the conveyer D, while on the front and also the back of conveyer C are sloping pans or floors 100, of sheet metal, adapted to receive the overflow and to return it to the conveyer. These pans connect with
55 a surrounding hopper 101, having sloping sides adapted to deliver coke from all directions upon the traveling slats, and for the full length of the conveyer D it is provided with a pan 102, having upwardly-extending
60 sides 103, upon which pan and between which sides travels the sprocket-chain and slats of the conveyer.

For the purpose of providing a quiet bearing for the slats the floor of said pan may be
65 provided with longitudinal strips of wood 104,

upon which the chains or slats are adapted to travel.

At any position in the length of conveyer D, but preferably near the front end, one or more openings are made in the floor, and below such openings is located the laterally-inclined dust-chute 105, adapted to receive the dust, which will fall through the slats and be drawn forward to such position at which it will fall by gravity and will discharge at 75 either side of the conveyer.

As will be understood, both conveyers operate continuously during the operation of the machine, and the handling of the coke is done automatically from the time it is drawn 80 to them from the oven.

Having described my invention, what I claim, and desire to secure by Letters Patent, is—

1. In combination with a coke-drawing machine provided with a longitudinally-movable rake; a transversely-arranged receiving-conveyer, an independent delivery-conveyer at an angle thereto, and means for driving both conveyers, substantially as set forth. 85

2. In combination with a coke-drawing machine provided with a longitudinally-movable rake; a transversely-arranged receiving-conveyer, an independent delivery-conveyer at an angle thereto, and means for driving both 95 conveyers at different speeds, substantially as set forth.

3. In combination with a coke-drawing machine provided with a longitudinally-movable rake; a transversely-arranged receiving-conveyer, a delivery-conveyer independent thereof and at right angles thereto, an intervening chute, and means for driving both conveyers, substantially as set forth. 100

4. In combination with a coke-drawing machine provided with a longitudinally-movable rake; a transversely-arranged receiving-conveyer, an independent delivery-conveyer at an angle thereto and at a lower level, an intervening chute, and means for driving both 110 conveyers.

5. In combination with a coke-drawing machine provided with a rake; a transversely-arranged receiving-conveyer, a delivery-conveyer independent thereof and provided with 115 a dust-chute, and means for driving both conveyers, substantially as set forth.

6. The combination with the receiving-conveyer of a coke-drawing machine, of a delivery-conveyer having its receiving end at a 120 lower level and provided with a pivoted vertically-adjustable extension, substantially as set forth.

7. The combination with the receiving-conveyer of a coke-drawing machine, of a delivery-conveyer having its receiving end at a lower level, and provided with a pivoted vertically-adjustable extension, and means for screening the coke, substantially as set forth. 125

8. In a coke-drawing machine, the combi- 130

nation of a main frame provided with a main shaft and a counter-shaft, a receiving and a delivery conveyer arranged at right angles to each other, and sprocket-wheels secured to the counter-shaft and main shaft respectively and connected by chains to the driving-shafts of the conveyers, substantially as set forth.

In testimony whereof I affix my signature in presence of two witnesses.

JOHN A. HEBB.
